United States Patent Office

Des. 211,110
Patented May 21, 1968

211,110

CLOCK

William Conlin, Freeport, N.Y. (½ General Time Corporation, High Ridge Park, Stamford, Conn. 06905)

Filed May 26, 1967, Ser. No. 7,335

Term of patent 14 years

(Cl. D42—7)

FIG. I

FIG.2

FIG.3

FIG.4

FIG. 1 is a front elevational view of a clock, showing my new design;

FIG. 2 is a rear elevational view;
FIG. 3 is a top plan view; and

FIG. 4 is right side elevational view. The essential features of the design are shown in full lines.

I claim:

The ornamental design for a clock, substantially as shown and described.
